UNITED STATES PATENT OFFICE

HENRY S. YOUNG, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY SWITCH CONTROLLING APPARATUS

Application filed January 22, 1931. Serial No. 510,338.

My invention relates to railway switch controlling apparatus, and particularly to the indication mechanism commonly provided in apparatus of that character for governing the movements of the switch controlling lever.

I will describe one form of apparatus embodying my invention, and will then point out the novel features thereof in claims.

10 The accompanying drawing is a diagrammatic view showing one form of apparatus embodying my invention.

Referring to the drawing, the reference character G designates a railway switch having the usual normal and reverse positions.

This switch is operated by a switch mechanism H, which, as here shown, is of the electropneumatic type, although other suitable types of mechanism can be used in connection 20 with my invention. The mechanism H is provided with the usual normal magnet N¹, reverse magnet R¹, and lock magnet Q, it being understood that when the normal and lock magnets are energized, the switch will be moved to its normal position, whereas when the reverse and lock magnets are energized, the switch will be moved to its reverse position.

The switch mechanism H is controlled by 30 a lever L having a normal position N, a reverse position R, a normal indicating position B, and a reverse indicating position D. Associated with the lever L is a detector lock A, comprising a segment 2 attached to the lever and co-acting with a dog 3 which is governed by an armature 5 of a magnet 4. This lock is so arranged that when the lever is in either the normal or the reverse position, the dog 3 will prevent movement of the lever unless the magnet 4 is energized to lift the dog out of the path of the shoulder on the segment. Also associated with the lever L is an indication lock C, comprising a segment 2^a attached to the lever and coacting with a dog 3 which is controlled by the armature 5 of a second magnet 4. This lock is so arranged that the lever cannot be moved beyond either indicating position unless the magnet 4 is energized to lift the dog 3 out of the central notch in the segment 2^a, although

the lever is free to move from either indicating position to the other while this magnet is deenergized.

The detector lock A and the indication lock C are controlled jointly by an indication relay E and an indication selector relay F.

The indication relay E is of the polarized type; as here shown, it is an induction motor relay having two stator windings 7 and 8, and a rotor 6 controlling two contacts 9 and 10. This relay will of course be provided with other contacts for the control of signals in accordance with usual practice, but such contacts do not enter into the present invention and are omitted from the drawing to simplify the disclosure. Winding 7 of relay E is constantly supplied with alternating current of fixed relative polarity from a suitable source, which is not shown in the drawing, but the terminals of which are designated X and Y. Alternating current of normal or reverse relative polarity is at times supplied to winding 8 by means hereinafter explained. The relay is so arranged that when winding 8 is supplied with current of normal relative polarity, front contact 9—9^a will be closed, whereas when winding 8 is supplied with current of reverse relative polarity and also when either winding of the relay is deenergized, back contacts 9—9^b and 10—10^b will be closed.

The circuit for winding 8 of relay E is supplied with alternating current from the terminals X and Y, and this circuit includes a pole-changer K¹ operated by the switch G, as well as a pole-changer K² operated by the lever L. The pole-changer K¹ is arranged to occupy its normal or its reverse position according as the switch is in its normal or its reverse position. The pole-changer K² comprises two contacts NB² and NB³, both of which are closed when the lever L occupies its normal position or its normal indicating position or any position between the two. This pole-changer also comprises two other lever-operated contacts RD² and RD³, both of which are closed when the lever occupies its reverse position or its reverse indicating position or any position between the two. The two pole-changers are so arranged that

- when the switch is in the normal position, current of normal relative polarity is supplied to winding 8 if the lever is in its normal to normal indicating positions, but current of reverse relative polarity is supplied to winding 8 if the lever is in its reverse to reverse indicating positions. Furthermore, when the switch G is in its reverse position, the current supplied to winding 8 is of normal relative polarity when the lever is in its reverse to reverse indicating positions, but of reverse relative polarity when the lever is in its normal to normal indicating positions.
- 15 The indication selector relay F is provided with a pick-up circuit which includes back contact 9-9^b of relay E and a BD contact operated by lever L. This relay is provided with a stick circuit which includes its own front contact 11 and the BD contact of lever L.
- 18 The circuit for magnet 4 of the detector lock A is from terminal X, through front contact 9-9^a of relay E, back contact 12-12^b of relay F, a latch contact M associated with lever L, and the winding of magnet 4 to terminal Y. The circuit for magnet 4 of the indication lock C includes front contact 9-9^a of relay E and front contact 12-12^a of relay F, and this circuit will be obvious from the drawing.
- 22 As shown in the drawing, the switch G is in its normal position, lever L is in its normal position, relay E is energized in normal direction, and relay F is deenergized.
- 25 I will now assume that the operator desires to move the switch G to its reverse position. To do this, he will close the latch contact M, thereby energizing magnet 4 of the detector lock A, so that the lever L will be released. He will then move this lever to the reverse indicating position D. This will open contacts NB² and NB³, and will close contacts RD² and RD³, so that winding 8 of relay E will be
- 30 supplied with current of reverse relative polarity, with the result that the front contact of this relay will open and the back contacts will close. The closing of back contact 10-10^b of relay E will energize the lock magnet Q, and the closing of lever contact RD¹ will energize the reverse magnet R¹, so that the switch mechanism H will operate to move the switch to its reverse position. The lever L cannot yet be moved beyond the D position.
- 35 because of the indication lock C. The closing of back contact 9-9^b of relay E will cause relay F to become energized, because the BD contact in the pick-up circuit for this relay will now be closed. Relay F will
- 40 then remain energized as long as the BD contact remains closed. When the switch reaches its reverse position, pole-changer K¹ will occupy its reverse position, with the result that current of normal relative polarity
- 45 will again be supplied to winding 8 of relay

E. The front contacts of this relay will then close, with the result that magnet 4 of the indication lock C will become energized to release lever L. This lever may then be moved to the reverse position R. The opening of back contact 10-10^b of relay E will deenergize lock magnet 4, so that the switch mechanism H will become locked in its reverse position.

70 The operation of the apparatus in order to restore the switch D to its normal position will be understood from the foregoing without detailed explanation.

75 It will be observed that the detector lock A cannot be energized unless the indication relay E is energized in normal direction and the indication selector relay F is de-energized. It will also be observed that apparatus embodying my invention permits the use of a two-element two-position indication relay E instead of the three-position relay now commonly used for this purpose.

80 The front contact 9-9^a of relay E is included in the circuit for the detector lock A for the purpose of insuring that relay E and lever L correspond in positions before the lever can be moved away from either its full normal or its full reverse position. This serves as a guarantee against premature indication due to improper energization of the indication relay E, because if anything should occur to cause false energization of winding 8 by current of reverse relative polarity, or if either winding of relay E should become deenergized, front contact 9-9^a of this relay will be opened and so will prevent energization of the detector lock magnet 4.

85 The purpose of including back contact 12-12^b of relay F in the detector lock circuit is, of course, to insure that the indication selector relay F is deenergized before the lever L can be moved away from either its normal or its reverse position. The purpose of the indication selector relay F is to insure that the front contacts of relay E will be opened during an operation of the switch, and this insurance is obtained by requiring the back contacts of relay E to be closed in order to permit relay F to become energized. In other words, the indication lock C cannot be energized unless relay F is energized, and relay F cannot be energized unless relay E has been deenergized.

90 Although I have herein shown and described only one form of apparatus embodying my invention, it is understood that various changes and modifications may be made therein within the scope of the appended claims without departing from the spirit and scope of my invention.

95 Having thus described my invention, what I claim is:

1. In combination, a railway switch having normal and reverse positions, a control lever for said switch having normal and re-

- verse positions as well as normal indicating and reverse indicating positions, a polarized indication relay having front contacts which are closed when the relay is supplied with 5 current of normal relative polarity and back contacts which are closed when the relay is supplied with current of reverse relative polarity and also when it is deenergized, means including a pole changer operated by the 10 switch and a pole changer operated by said lever and operating when the switch is in normal position to supply said relay with current of normal relative polarity if the lever is in normal-to-normal indicating positions and with current of reverse relative polarity if the lever is in reverse-to-reverse indicating positions, said means also operating when the switch is in reverse position to supply the relay with current of normal relative polarity if the lever is in reverse-to-reverse indicating positions and with current of reverse relative polarity if the lever is in normal-to-normal indicating positions, an 15 indication selector relay having a pick-up circuit including a back contact of said indication relay and a normal indicating to reverse indicating contact of said lever, a stick circuit for said indication selector relay including said same lever contact but excluding 20 said indication relay contact, a detector lock for said lever, means for releasing said lock if and only if the front contacts of said indication relay are closed and said indication selector relay is deenergized, an indication lock for said lever, and means for releasing said indication lock if and only if the front contacts of said indication relay are closed and said indication selector relay is energized. 25
2. In combination, a railway switch having normal and reverse positions, a control lever for said switch having normal and reverse positions as well as normal indicating and reverse indicating positions, a polarized indication relay having front contacts which are closed when the relay is supplied with current of normal relative polarity and back contacts which are closed when the relay is supplied with current of reverse relative polarity and also when it is deenergized, means including a pole-changer operated by the switch and a pole-changer operated by said lever and operating when the switch is in normal position to supply said relay with current of normal relative polarity if the lever is in normal-to-normal indicating positions and with current of reverse relative polarity if the lever is in reverse-to-reverse indicating positions, said means also operating when the switch is in reverse position to supply the relay with current of normal relative polarity if the lever is in reverse-to-reverse indicating positions and with current of reverse relative polarity if the lever is in normal-to-normal indicating positions, and 30 means for controlling the movements of said lever by said indication relay.
3. In combination, a railway switch, a lever for the control of said switch, a polarized indication relay having front contacts which are closed when the relay is supplied with current of normal relative polarity and back contacts which are closed when the relay is supplied with current of reverse relative polarity and also when it is deenergized, means for supplying said relay with current of normal relative polarity when said switch and lever harmonize in positions and with current of reverse relative polarity in response to an initial switch operating movement of the lever, an indication selector relay, means for energizing said selector relay when said lever has been moved to an initial switch operating position and said indication relay back contacts are closed, and for thereafter keeping the selector relay energized until the movement of the lever is completed, means for preventing an initial movement of said lever unless the front contacts of said indication relay are closed and said selector relay is energized. 35
4. In combination, a railway switch, a lever for the control of said switch, a polarized indication relay having front contacts which are closed when the relay is supplied with current of normal relative polarity and back contacts which are closed when the relay is supplied with current of reverse relative polarity and also when it is deenergized, means for supplying said relay with current of normal relative polarity when said switch and lever harmonize in positions and with current of reverse relative polarity in response to an initial switch operating movement of the lever, and means for controlling the movements of said lever by said indication relay. 40
5. In combination, a railway switch having normal and reverse positions, a control lever for said switch having normal and reverse positions as well as normal indicating and reverse indicating positions, a polarized indication relay having front contacts which are closed when the relay is supplied with current of normal relative polarity and back contacts which are closed when the relay is supplied with current of reverse relative polarity and also when it is deenergized, means including a pole-changer operated by the switch and a pole-changer operated by said lever and operating when the switch is in normal position to supply said relay with current of normal relative polarity if the lever is in normal-to-normal indicating positions and with current of reverse relative polarity if the lever is in reverse-to-reverse indicating positions, said means also operating when the switch is in reverse position to supply the relay with current of normal relative polarity if the lever is in reverse-to-reverse indicating positions and with current of reverse relative polarity if the lever is in normal-to-normal indicating positions and with current of reverse relative polarity if the lever is in reverse-to-reverse indicating positions, said means also operat- 45 50 55 60 65 70 75 80 85 90 95 100 105 110 115 120 125 130

ing when the switch is in reverse position to supply the relay with current of normal relative polarity if the lever is in reverse-to-reverse indicating positions and with current of 5 reverse relative polarity if the lever is in normal-to-normal indicating positions, an indication selector relay having a pick-up circuit including a back contact of said indication relay and a normal indicating to 10 reverse indicating contact of said lever, a stick circuit for said indication selector relay including said same lever contact but excluding said indication relay contact, and means for controlling the movements of said lever by 15 said two relays.

6. In combination, a railway switch, a lever for the control of said switch, a polarized indication relay having front contacts which are closed when the relay is supplied with 20 current of normal relative polarity and back contacts which are closed when the relay is supplied with current of reverse relative polarity and also when it is deenergized, means for supplying said relay with current 25 of normal relative polarity when said switch and lever harmonize in positions and with current of reverse relative polarity in response to an initial switch operating movement of the lever, an indication selector relay, 30 means for energizing said selector relay when said lever has been moved to an initial switch operating position and said indication relay back contacts are closed, and for thereafter keeping the selector relay energized until 35 the movement of the lever is completed, and means for controlling the movements of said lever by said two relays.

7. In combination, a railway switch having normal and reverse positions, a control lever 40 for said switch having normal and reverse positions as well as normal indicating and reverse indicating positions, a polarized indication relay having front contacts which are closed when the relay is supplied with 45 current of normal relative polarity and back contacts which are closed when the relay is supplied with current of reverse relative polarity and also when it is deenergized, means including a pole-changer operated by 50 the switch and a pole-changer operated by said lever and operating when the switch is in normal position to supply said relay with current of normal relative polarity if the lever is in normal-to-normal indicating positions and with current of reverse relative polarity if the lever is in reverse-to-reverse indicating positions, said means also operating when the switch is in reverse position to 55 supply the relay with current of normal relative polarity if the lever is in reverse-to-reverse indicating positions and with current of reverse relative polarity if the lever is in normal-to-normal indicating positions, an indication selector relay having a pick-up circuit including a back contact of said indica- 60

tion relay and a normal indicating to reverse indicating contact of said lever, a stick circuit for said indication selector relay including said same lever contact but excluding said indication relay contact, means for preventing an initial movement of said lever unless the front contacts of said indication relay are closed and said selector relay is deenergized, and means for preventing completion of a movement of said lever unless the front contacts of said indication relay are closed and said selector relay is energized.

In testimony whereof I affix my signature.
HENRY S. YOUNG.
